(57) **CLAIM**

I claim the ornamental design for a golf putting practice hole simulator, as shown and described.

DESCRIPTION

FIG. 1 is a perspective view of the invention with a flag pole portion cut out to illustrate that it is longer than as shown. Omitted portions of the pole are configured the same as portions shown.

FIG. 2 is a right side view of the invention, the left side view, front view and rear view being a mirror image thereof.

FIG. 3 is a top plan view of the invention; and,
FIG. 4 is a bottom plan view of the invention.

The broken lines in FIG. 1 showing one possible flag configuration and showing the outline of two golf balls trapped by the simulator are for purposes of illustration only and form no part of the claimed design.
